CORROSION INHIBITOR

William J. Sweeney, Westfield, and Emile L. Baldeschwieler, Cranford, N. J., assignors to Standard Oil Development Company, a corporation of Delaware

No Drawing. Application March 4, 1939,
Serial No. 259,902

7 Claims. (CL 23—239)

This invention relates to compositions for protecting metals of various kinds from corrosion, especially metals that are used in the construction of containers for various fluids.

5 Airports provided with wide level flying fields over which the planes taxi when taking off and when landing must be provided with fueling stations. The ordinary upstanding meter casings almost universally used in automobile fueling 10 stations for dispensing gasoline are objectionable on such fields because of the danger of their being struck by taxiing planes. Fueling outlets that are suitable are those that may be submerged so that when not in use they are covered, leaving a clear open flying field. As all the working parts 15 of fueling stations are at times covered over, being below the level of the flying fields, the use of pumps is avoided for obvious reasons, such as water flooding, etc. Therefore, the containers used for gasoline are generally connected with city 20 mains whereby the pressure of the city mains is used to force the gasoline from the containers to the various tanks of the planes. The containers are also connected to the sewer so that when 25 being filled with gasoline the water may flow out through the sewer outlet. One of the difficulties encountered in using water in a system of this particular type is the corrosion that results. The tanks are composed of metals, such as iron, 30 aluminum, brass, zinc, etc., and generally tend to corrode. The ordinary corrosion inhibitors used to prevent corrosion are water soluble and necessarily need be added continuously as more water is added, as the first part is lost for further use as the water is allowed to flow to the sewer. The gasoline stored in this manner, when 35 run into tanks to be used to run motors, may carry some water over mechanically or dissolved therein, after which it is precipitated by a drop 40 in temperature and it is desirable that this water also be treated so that no corrosion will take place in the tanks. In the handling of other fluids, such as heavier oils or greases, corrosion also results when water is present, especially 45 when in free acid or when alkali is present.

It is an object of this invention to provide an inhibitor that may be added to a metal container for fluid to prevent corrosion of the metal container, though varying amounts of the fluids stored therein may be added and removed a number of times.

Another object is to prevent corrosion in storage vessels for greases and oils, especially compounded oils where there may be some settling of

the soap, which on hydrolysis forms corrosive compounds.

A further object of this invention is to provide an inhibitor which is substantially inert and not readily soluble that will prevent corrosion of 5 containers used for storage of various compositions which tend to corrode the containers.

According to this invention, it has been found that the yellow, very slightly water-soluble alkali salts of uranium will inhibit corrosion of metals, 10 particularly the corrosion of aluminum. Aluminum, when submerged in water containing 2% of sodium chloride, after 96 hours shows a loss in weight of 0.9 milligram per gram. On the other hand, if the water has .02% of yellow sodium 15 uranate in solution, after 96 hours there is no loss in weight of the aluminum when submerged in water containing 2% of sodium chloride. Both the yellow sodium and ammonium uranates were 20 found to be effective and as they are slightly 25 soluble in water, they may be introduced into the container and confined in a narrow space by means of a fabric, such as a porous cloth bag. The water circulating through the container will 30 only remove a very slight amount of the uranates 35 at each throughput, that is, as the tank is filled with water and emptied, there is only a very little loss of the corrosion inhibitor. In greases and oils where the presence of the yellow sodium or ammonium uranate is not objectionable, they 40 may be added in proportions of about .02% to prevent corrosion of the metal that may be caused by separation of the water. In liquids or oils where there may be some accumulation of water that had been mechanically carried over or precipitated out by the change in temperature, a small bag or fabric container filled with sodium and ammonium uranates retained at the lowest 45 part of the container will inhibit corrosion.

Effect of yellow alkali uranates on aluminum corrosion. Aluminum metal sheet half immersed in distilled water covered with gasoline

Inhibitor	Hours of standing before corrosion	45
None	304	
0.02% potassium dichromate	634	
0.02% ammonium uranate	802	50
0.02% yellow sodium uranate	802	

We claim:

1. A method of inhibiting corrosion in a metal container containing a motor fuel which com- 55

- prises suspending in the lower part of the metal container a porous cloth bag containing yellow, very slightly water-soluble alkali uranates.
2. A method of inhibiting corrosion in a metal container containing a motor fuel which comprises suspending in the lower part of the metal container a porous cloth bag containing yellow sodium uranate.
3. A method of inhibiting corrosion in a metal container containing a motor fuel which comprises suspending in the lower part of the metal container a porous cloth bag containing yellow ammonium uranate.
4. A process for preventing deterioration of naphtha comprising maintaining the product in liquid condition in direct contact with a yellow, very slightly water-soluble mono-valent salt of a yellow uranate.
5. A method of inhibiting corrosion in a metal
